CLAIM

The ornamental design for an exhalation port for a breathing circuit, as shown and described.

DESCRIPTION

FIG. 1 is a perspective view showing a front side of an exhalation port for a breathing circuit, showing our new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The dashed broken lines in the drawings illustrate portions of the exhalation port for a breathing circuit which form no part of the claimed design. The dot-dash broken lines define the bounds of the claimed design and forms no part thereof.
